UNITED STATES PATENT OFFICE.

SAMUEL MILNE, OF EDINBURGH, SCOTLAND.

PAPER PULP AND LIKE BEATING ENGINE.

Application filed November 3, 1926, Serial No. 145,981, and in Great Britain November 23, 1925.

This invention relates to paper pulp and like beating engines.

The main feature of the invention is an improved arrangement and combination of bed-plate, "backfall," beater roll supporting means, and beater cover. Other features are means for causing the pulp which is thrown off by the ends of the roll to pass over the periphery of the roll, and means for preventing the pulp passing between the ends of the roll and the cover from the side next the "backfall." A further feature is an improved shape of tank, and improved means for circulating and mixing the pulp in the tank, the whole of the improvements combining to provide a highly efficient beating engine.

The invention will be fully described with the aid of the accompanying drawings, 20 wherein:—

Fig. 1 illustrates a longitudinal section of a pulp beating engine constructed according to the invention.

Fig. 2 illustrates a cross-section of the roll 25 cover on line α , α of Fig. 1.

Fig. 3 illustrates a plan of Fig. 1.

Fig. 4 illustrates a longitudinal section of an alternative construction of beater embodying the invention.

Fig. 5 illustrates a side elevation of roll 30 balancing gear used with the improved beater.

Fig. 6 illustrates a side or face view of a detached detail part of Fig. 4.

Fig. 7 illustrates a plan (in part) of the 35 beater and shows an improved form of tank.

a is the tank which may be made either to the shape (in plan) shown in Fig. 3, or to the shape (in plan) shown in Fig. 7. b is

40 a midfeather dividing the tank longitudinally and c is the beater roll arranged between said midfeather and one side of the tank. d is the bedplate which lies in a recess d' formed in the floor of the trough. Such

45 bedplate extends from the vertical plane passing through the axis of the roll c to a point where the tangential portion of the backfall e commences, and extends through an arc of approximately 75° . The back-

50 fall e lies close to the roll and extends to a height of about one half the radius of the roll above the axis of same, and the front face is formed in a straight line tangent to the roll and at an angle of about 15° to the vertical.

The roll c is supported in bearings carried

by levers c^1 which are adjustable through worm and worm wheel gearing c^2 and are adapted to move the roll bodily at an angle of about $37\frac{1}{2}^\circ$ from the vertical. Upon the 60 roll axis or trunnion is a pulley f by which and a belt f' it is driven from any suitable source of power. In Figs. 4 and 5, balance weights g are provided, which are adjustably carried on a screw g^1 mounted on the 65 pivoted arm h of a stand i , and which, through the medium of the link k , long lever arm k^1 , regulating screw k^2 , and worm gear c^2 , balance the roll and allow of the easy adjustment of the roll in relation to 70 the bedplate.

With the roll c mounted as described it is adapted to move towards and away from the bedplate in a diagonal path, thus always adapting itself to the bedplate, and 75 with the bedplate arranged to come up to the backfall, and the backfall tangential to same and close to the beater roll, the pulp does not lose its velocity and can be discharged immediately it passes clear of the bedplate. 80

To prevent the pulp contacting with the roll on the lower side furthest from the bedplate, the cover m on such side is extended down towards the floor of the tank, and forms a baffle or guard plate m^1 which meets the impact of the pulp as it flows towards the roll and thus minimizes the resistance to turning of the roll and/or reduces the power required to drive the roll. The floor of the trough where it meets the bedplate is stepped 85 or curved downwards at n as shown, instead of being flat and level with the bedplate, thereby allowing ample room for the pulp to flow to the roll at such point.

The cover m is shaped to enclose the roll 90 c and may be mounted so as to be capable of adjustment towards and away from the roll. That part of the cover above and in connection with the backfall is made curved in shape so that the pulp striking it is deflected with the least possible loss of energy and caused to fall beyond the top edge of the backfall where it cannot interfere with the pulp being discharged by the roll. This part of the cover is brought down to be 100 quite close to the roll, and the point where it meets the roll may be level with or only slightly higher than the top of the backfall to ensure a sufficient arc of the circumference to effect the discharge of pulp from 105 the roll.

To help to further break up and mix the

pulp, one or more diagonally disposed angle strips o carried by a frame p , see Fig. 6, may be secured within the cover m the pulp, as it passes over the backfall, being deflected

5 to one side by the strips o and caused to mix more fully than if such strips were not provided.

In Fig. 1 the backfall is composed partly of the metal of the trough and partly of a 10 wood bar e^1 , which allows of the height of the backfall being readily varied by substituting bars of different depth. Said bar may be secured to the cover m and be removable. In Fig. 4, the backfall is wholly 15 of metal.

To deflect the pulp over the working face of the roll as it is thrown radially outwards by the roll ends, the roll cover m is formed with angular corner faces m^2 see Fig. 2. 20 Such angular faces extend all round the cover, but they may only extend around the upper portion of the cover. By means of said angular faces pulp is prevented lodging in the angles or corners of the cover and all 25 the pulp comes in for treatment by the roll.

In the angular spaces between the backfall, Fig. 1, and the roll, and at points opposite the spaces between the roll ends and the sides of the trough, filling strips q are 30 applied, which serve to prevent the pulp, after reaching the backfall, flowing back alongside the roll.

To provide for the even circulation and agitation of the pulp, a slowly rotating paddle or agitator may be provided at one end 35 of the trough, see Figs. 1 and 3. This paddle or agitator is preferably composed of two wood blades r , r and a circular metal part s^1 from which the blades are rigidly suspended. The paddle or agitator is mounted 40 on a vertical spindle u journaled in a fixed bearing v , and rotated by worm wheel w , and worm x , driven say through belt pulleys y and belt z from the roll shaft. The bearing v may be part of a metal casing v^1 supported above the trough by a bracket v^2 and 45 cross beams v^3 .

As shown in Fig. 1, the blades sweep close to the outer wall of the trough and close to 50 the edge of the mid-feather b of the trough, and the effect on the pulp as the paddle rotates is to assist the movement of the pulp next the outer wall of the trough and to retard the flow of the pulp next the mid-feather. In this way the flow of the pulp is 55 equalized and the pulp is also effectually mixed.

The mixing paddle may not always be used, and in Fig. 4, it is shown omitted.

60 Instead of being made semi-circular in plan at each end, the trough may be made as shown in Fig. 7, the round or arched parts b^1 being struck from a radius taken from the end of the mid-feather b and joined by a 65 tangent or flat b^2 extending at an angle to

the side of the tank. This shape of tank prevents lodgment of the pulp in the otherwise curved parts and the slower circulation of the pulp at such parts.

What I claim is:—

70 1. A paper pulp or like beating engine comprising a tank, and a longitudinal mid-feather in said tank, a beater roll between said mid-feather and one side of the tank, bearings for said roll, levers carrying said 75 bearings, and worm and worm wheel mechanism for adjusting said levers, and regulatable balance weights for said levers and roll, a backfall lying close to said roll and extending at a slight angle above the level of 80 the roll axis, a bedplate for said roll extending towards the backfall through an arc of about 75° and a cover closely fitting and covering in the roll and also covering in the backfall, that part of the cover fitting the 85 roll having angled or sloping faces opposite the spaced between itself and the roll ends and on the side next the backfall having filling strips, and on that side of the roll furthest from the backfall said cover extending down to a point near the floor of the tank, as set forth.

2. A paper pulp or like beating engine, comprising a tank, and a longitudinal mid-feather, a beater roll between said mid-feather and one side of the tank, bearings for said roll, levers carrying said bearings and worm and worm wheel mechanism for adjusting said levers, and regulatable balance 90 weights for said levers and roll, a backfall lying close to said roll and extending at a slight angle above the level of the roll axis, a bedplate for said roll extending towards the backfall through an arc of about 75° and a cover closely fitting and covering in the roll and also covering in the backfall, that part of the cover fitting the backfall being arched or curved and having within it diagonally disposed angle strips for diverting 95 and mixing the pulp as it passes over the backfall, and that part of the cover furthest from the backfall extending down to a point near the floor of the tank, as set forth.

100 3. A paper pulp or like beating engine, comprising a tank, and a longitudinal mid-feather in said tank, a beater roll between said mid-feather and one side of the tank bearings for said roll, levers carrying said 105 bearings and worm and worm wheel mechanism for adjusting said levers, and regulatable balance weights for said levers and roll, a backfall lying close to said roll and extending at a slight angle above the level of the roll axis, a bedplate for said roll extending towards the backfall through an arc of about 75° and a cover closely fitting and covering in the roll and also covering in the backfall, that part of the cover furthest from the backfall extending down in the form of 110 115 120 125 130

a baffle plate to a point near to the tank floor, and that part nearest said backfall extending down close to the periphery of the roll, and then extending upwards and over the backfall, such last named part being arched or curved to allow the pulp to pass freely over the backfall, a rotary paddle and vertical

axis therefor opposite one end of the mid-feather, means for rotatably supporting said paddle, and means for rotating the paddle, ¹⁰ as set forth.

In testimony whereof I have signed my name to this specification.

SAMUEL MILNE.
